LEG SUPPORT FOR WHEEL CHAIRS

Charles C. Gates, Jr., Denver, Colo.

Application July 3, 1950, Serial No. 171,882

14 Claims. (Cl. 155—165)

1

This invention relates to leg rests for chairs, and more particularly to invalids' wheel chairs.

One of the objects of the invention is to provide a single leg rest for a chair which may be removably attached thereto in two different positions for supporting either leg of the invalid.

Another object is to provide means for adjusting the position of the rest in a direction to or from the chair seat and also in a vertical plane relative thereto.

Another object is to provide an adjustment of the foregoing type wherein the rest is telescopically supported by the chair.

Another object is to provide a rest for wheel chairs of the folding type which permits the folding thereof without removing the rest therefrom.

Another object is to provide a rest for wheel chairs of the non-folding type.

A further object is to provide a rest which may be readily attached to conventional wheel chairs.

Another object is to provide a foldable rest to accommodate both legs of the invalid.

Further objects, advantages, and salient features will become more apparent from a consideration of the description to follow, the appended claims, and the accompanying drawing, in which:

Figure 1 is a perspective of a conventional folding type wheel chair to which one form of the subject of the invention has been applied;

Figure 2 is an enlarged fragmentary front elevation thereof in the direction of arrow 2, Figure 1, with the rest removed;

Figure 3 is a bottom plan view of the chair seat as viewed in the direction of arrow 3, Figure 1;

Figure 4 is an enlarged section taken on line 4—4, Figure 3;

Figure 5 is a similar section taken on line 5—5, Figure 3;

Figure 6 is an enlarged section taken on line 6—6, Figure 1;

Figure 7 is a fragmentary side elevation of a vertical leg rest adjusting means which may be employed in any of the various modifications of the invention;

Figure 8 is a top plan view, in the direction of arrow 8, Figure 7, portions being broken away;

Figure 9 is a fragmentary perspective, similar to Figure 1, of a conventional wheel chair of the sling seat type to which an alternative form of the subject of the invention has been applied;

Figure 10 is an enlarged foreshortened bottom

2

plan of the chair of Figure 9 taken in the direction of arrow 10, Figure 9;

Figure 11 is an exploded isometric view of an alternative form of leg rest which may be employed with the chairs of Figure 1 or 9;

Figure 12 is a vertical section taken on line 12—12, Figure 11, but with the parts in assembled relation;

Figure 13 is an isometric view of an alternative form of leg rest which may be employed with the chair of Figure 1;

Figure 14 is a foreshortened top plan of an alternative form of leg rest which may be employed with the chair of Figure 1; and

Figure 15 is a side elevation of an alternative form of leg rest adjustment.

Referring in detail to the drawing, and particularly Figures 1 to 3, the wheel chair 20 is provided with a plurality of tubular members which comprise a frame 21, arm rests 22, 22a, back rest 23 supporting drive wheels 24, 24a, swivel wheels 25, 25a, foldable foot rests 26, 26a and folding seat 27, 27a, the foregoing all being conventional and well-known in the art. Certain of the frame members are adjustable so that the two halves of the seat 27, 27a may be folded relatively in the direction of arrows 28, 28a, Figure 2, so that the bottom surfaces thereof may be disposed in substantially parallel juxtaposed relation, the dotted line position of Figure 2 illustrating the seat halves in partially folded relation. Since the particular details for effecting folding of the seat and remainder of the chair form no part of the invention per se, these details have been omitted in the interest of clarity.

The chair just described is normally provided with hinges (not shown) secured to the lower surfaces of the seat halves 27, 27a which permit the pivotal movement illustrated in Figure 2. When the subject of the invention is to be applied as an attachment to the conventional chair these hinges are removed and replaced with a special form of hinge and tube construction.

45 This construction comprises a tube 30 (see Figure 3) having hinges secured thereto near its ends. Each hinge is provided with a member 31 having a pair of tubular portions 32, 33 which surround tube 30, member 34 being secured in any suitable manner to seat half 27a. A member 34, having a tubular portion 35 disposed between portions 32, 33, similarly surrounds tube 30, member 34 being similarly secured to seat 50 half 27. Tube 30 is prevented from axial move-

55 half 27. Tube 30 is prevented from axial move-

ment relative to the hinges in any manner desired.

A pair of tubes 36, 36a (see Figure 3), preferably of the same inside diameter as tube 30, are secured to the seat halves in parallel relation to tube 30 and equidistant therefrom in any suitable manner, such as by brackets 37, 37a welded to the respective tubes.

The leg rest comprises a pair of parallel tubes 40, 40a disposed in parallel relation, connected by a curved bight portion 41, this forming a U-shaped frame the legs of which selectively telescope within two of the three tubes secured to the bottom of the seat. When the rest is employed to support the right leg, tubes 40, 40a are disposed, respectively, within tubes 36, 30 and when employed to support the left leg, tubes 40, 40a are disposed, respectively, within tubes 30, 36a. A suitable flexible sling member 42 of canvas, webbing, or the like, extends between tubes 40, 40a and forms a cradle in which a leg may be supported.

The leg support just described is adjustable only in a direction to and from the seat. If the refinement of an adjustment in a vertical plane is also desired tubes 40, 40a may be provided with an adjustment as shown in Figures 7 and 8 wherein each of the tubes has interposed therein, preferably adjacent the rear edge of flexible member 42, a pair of plates 43, 44, each being secured to one of the adjacent ends of the tubes, and secured together by a bolt and wingscrew 45, or the like. The faces of the disks may be serrated if desired to improve their clamping characteristics. It will be apparent that with this construction tubes 40, 40a still adjustably telescope within the tubes secured to the seat and the portion of the leg support carrying flexible member 42 may be adjusted in a vertical plane, swinging about the axes of disks 43, 44.

In the construction so far described it will be apparent that the three tube support on the seat may be employed regardless of whether or not the seat is hinged along its central longitudinal axis. If the seat is of the non-foldable padded type, the tube 30 with its associated hinges may be omitted and in lieu thereof a tube such as 36 or 36a be employed in its stead. In some seat constructions, however, such as those which employ a flexible sling material secured to the chair along the side edges of the seat, similar to the construction of member 42, the center support tube may preferably be omitted and only two side tubes employed. In Figures 9 and 10 such sling seat construction 127 is illustrated wherein tubes 136, 136a are analogous to tubes 36, 36a and are secured to the chair frame or seat in any suitable manner. Tubes 140, 140a are substantially the same as tubes 40, 40a and the same distance apart, but tube 140a is provided with a lateral offset portion 140b which connects to a portion 140c which is parallel to tube 140. The leg support of this construction may be employed for either the left or right leg by merely removing it from its support tubes, rotating it 180 degrees about its longitudinal axis, and reinserting it in the support tubes.

The vertical adjustment means of Figures 7 and 8 may be employed with tubes 140, 140a in the same manner previously described, these adjustments being disposed between sling 142 and the chair seat.

If the chair of Figures 9 and 10 be of the folding type which folds in a manner similar to the chair of Figures 1 and 2, it will be apparent that

the leg rest 140, 140a, etc., must be removed from tubes 136, 136a when folding is desired. To obviate the necessity of removing the leg support when the chair is folded, the construction shown in Figures 11 and 12 may be employed. In this construction a U-shaped member 240d is welded or otherwise secured to an end of tube 240a and is apertured near one end to permit tube end 240e to pass therethrough and telescope with tube 240a, as best shown in Figure 12. The legs of U-shaped member 240d may be slightly resilient so that tube 240b may be releasably supported thereby. When it is desired to fold the chair, tube 240b is withdrawn from its connection with U-shaped member 240d, as shown in Figure 11, after which the chair may be folded about its longitudinal axis. It will be apparent, also, that the support just described may be used in the construction shown in Figures 1 and 2, in which case tube 30 may be omitted.

In Figure 14 is shown a form of double leg rest which may be employed in the construction shown in Figures 1 and 2, this rest comprising tubes 340, 340a, connected by bight portion 341, and tubes 340b, 340c, similarly connected. Tube 340c is provided with a tubular portion 340d hingedly connecting it to tube 340a so that the two frame halves may pivot about the longitudinal axis of tube 340a. A sling 342, similar to sling 142, extends across the two frames and provides a support for both legs. It will be apparent that when tubes 340, 340a, 340b are supported by tubes 36a, 30, 36 of Figures 1 and 2, the leg support may be adjusted to and from the chair seat and the chair may be folded as shown in Figure 2 without removing the leg rest from its support tubes on the chair seat.

In Figure 13 is shown another leg rest which may be employed with Figures 1 and 2, this rest comprising tubular members 440, 440a which have offset portions 440b. This construction permits leg rest portion 442 to be disposed above the chair seat or below same, depending upon the particular manner in which it is inserted in the seat support tubes, it being apparent that it has two positions 180 degrees apart and the two limits of adjustment are a vertical distance apart equal to twice the amount of offset effected by portions 440b. It will be apparent that the adjustments of Figures 7 and 8 may also be employed in this construction or in any of the other constructions previously described.

In Figure 15 another type of vertical adjustment is disclosed wherein the support tubes, one of which is shown at 436, are pivotally connected at their rear ends by a pivotal connection 50 to the chair and are adjustable in a vertical plane, being secured in a desired position by a slotted member 51, secured to the chair, and a wing nut 52, or the like, carried by the tube and clampable to member 51.

Having described the invention, what is claimed as new is:

1. In a chair having a seat foldable about a longitudinal axis substantially centrally thereof, a tubular member disposed below the seat coaxial with said axis, a pair of tubular members disposed below the seat, on opposite sides of the first named tubular member, and equidistant and parallel thereto, an elongated U-shaped frame having parallel leg portions adapted to telescope, selectively, in the first named tubular member, and one of said pair of members, whereby the frame may be disposed on either side of the longitudinal axis of the

chair to support either the right or left leg of a user, and means extending between portions of the legs of the frame adapted to engage and support a leg of the user.

2. In a chair in accordance with claim 1 including means for adjusting said frame in a vertical plane.

3. In a chair having a seat, a pair of parallel tubular members disposed below the seat adjacent side edges thereof, a U-shaped frame having parallel leg portions adapted to extend forwardly of the seat to form a leg support of substantially less width than the seat and adapted to support only one leg of a user, the free ends of said leg portions being parallel and adapted to telescope within said tubular members, in two positions 180 degrees apart around a longitudinal axis of the U-shaped frame, whereby the U-shaped frame is adapted to selectively support either leg of the user.

4. In a chair in accordance with claim 3 including means for adjusting at least a portion of said U-shaped member in a vertical plane whereby its vertical position relative to the seat may be varied.

5. A chair having a seat, a pair of tubes secured to the chair in spaced parallel relation adjacent the seat and parallel to its longitudinal axis, an elongated leg supporting frame comprising a pair of parallel members having portions telescopically disposed within the tubes, and a sling extending between other portions of the members adapted to support a leg of the user, the last named portions being spaced apart a distance approximately equal to one-half the width of the seat transversely of said longitudinal axis.

6. A chair in accordance with claim 5 wherein said last named portions are disposed in a plane spaced from a plane passing through the first named portions.

7. A chair in accordance with claim 5 wherein one of the first named portions is detachably connected to one of the last named portions.

8. A chair in accordance with claim 5 wherein the first named portions are spaced apart a distance greater than the last named portions.

9. A chair in accordance with claim 5 including means interposed between the first and last named portions for angularly adjusting said first and last portions about a horizontal axis, whereby the sling may be raised or lowered relative to the seat.

10. A chair having a seat, a pair of tubes secured to the seat adjacent and below its longitudinal edges, one at each edge, a third tube secured to the seat midway between and parallel to said pair of tubes, an elongated leg support-

ing frame having at least two parallel members having portions adapted to be telescopically disposed within two of the three tubes, and means extending between other portions of the members adapted to support a leg of the user.

11. A chair in accordance with claim 10 wherein the leg supporting frame is provided with three parallel tubular members, each having a portion adapted to be telescopically disposed within one of the respective three tubes.

12. A chair in accordance with claim 10 including means for angularly adjusting said tubes about a horizontal axis, whereby said other portions may be adjusted in a vertical plane.

13. In a chair having a seat, an elongated device having a leg supporting portion of a width substantially less than the width of the seat, adapted to support only one leg of the user of the chair, means comprising at least two spaced tubular members on the chair beneath the seat thereof telescopically engaging transversely spaced portions of the leg supporting device, adapted to support same in a position wherein in the leg supporting portion forms a forward extension of the chair seat, said means and device being so constructed that said device may be bodily removed from the chair and disposed in two alternative predetermined positions wherein the leg supporting portion is disposed on either side of and substantially equidistant from a longitudinal axis of the seat whereby it may support either a right or a left leg.

14. In a chair defined by claim 13 wherein said means beneath the seat includes three tubular members, one being disposed substantially at a longitudinal central axis of the chair, and below the seat, and the other two being disposed at opposite sides of the first named tubular member and below the seat, parallel and equidistant from the first named tubular member.
